United States Patent Office

Des. 234,222
Patented Jan. 28, 1975

234,222

ELECTRIC LANTERN

Daniel C. Oakley, Madison, Nolan K. Rhoades, Beloit,
and Arthur R. Schmidt, Madison, Wis., assignors to
ESB Incorporated

Filed Nov. 13, 1972, Ser. No. 306,001

Term of patent 14 years

Int. Cl. D26—02

U.S. Cl. D48—24 R

Fig. 2

Fig. 3

Fig. 4

FIG. 1 is a front view of an electric lantern showing our new design.

FIG. 2 is a side view thereof with the lens casing in an alternate position.

FIG. 3 is a top view of the lantern as it appears in FIG. 2.

FIG. 4 is a bottom view of the lantern as it appears in FIG. 2.

We claim:

The ornamental design for an electric lantern, as shown and described.
